CLAIM

The ornamental design for a display screen with a graphical user interface for an assistive agent, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of an image of a display screen with a graphical user interface.

The broken lines show portions of the graphical user interface that form not part of the claimed design. The outer rectangle in broken lines is included to illustrate a portion of a display screen and forms no part of the claimed design.
